UNITED STATES PATENT OFFICE.

E. F. SHERMAN, OF CHICOPEE FALLS, MASSACHUSETTS.

IMPROVEMENT IN CORN-SHELLERS.

Specification forming part of Letters Patent No. 57,393, dated August 21, 1866.

To all whom it may concern:

Be it known that I, E. F. SHERMAN, of Chicopee Falls, Hampden county, Commonwealth of Massachusetts, have invented a new and Improved Corn-Shell; and I do hereby declare that the following is a full and exact description thereof, reference being had to the accompanying drawings, and to letters of reference marked thereon.

In the drawings, Figure 1 is a plan view of my improved sheller, and Fig. 2 a cross-section through the same.

In construction this invention consists of a cylinder, A, hung in a suitable frame, B, and studded with teeth *a a*. This cylinder is hung on journals *b b*, so as to revolve. In connection with this I use the case or bonnet C, partially surrounding the cylinder, and also studded on the inside with teeth. This case or bonnet is hung to the spring D at the top, which is attached to the side pieces, *dd*, which are adjustable at *ee* by means of the set-screws *h h*, working in slot *kk*. At the lower end it is hung on the spring E, which is adjustable inward toward the cylinder by means of the slotted pieces *ff*, fastened by means of the set-screws *gg*, and also the pressure of the spring may be regulated by means of the set-screw *l*. I also place the belt F on the rollers G for the purpose of feeding the ears of corn to the sheller; and the ledges H are formed on this belt for the purpose of holding the same on and carrying them up

to the opening between the cylinder and bonnet. I can also attach a hopper for holding the corn above this belt, as shown by the red lines.

The operation of my invention is as follows: The bonnet C being adjusted the proper distance from the cylinder, the cylinder is then revolved by turning the crank, or it may be turned by power applied at the same place by means of a pulley. Motion is communicated to the feed-belt F by the belt *o* and pulley *p*. Corn in the ear being then put on the feed-belt or in the hopper, the cylinder is revolved and the corn scraped or torn off from the cob while passing through the space between the cylinder and bonnet and falls into the trough M. Over this trough I sometimes place a separator, (not shown in the drawings,) consisting of a wire sieve coarse enough to allow the corn to pass through, but which holds the cobs.

Now, having described my invention, what I claim as new, and desire to secure by Letters Patent, is—

The combination of the cylinder A, bonnet C, teeth *a*, belt F F, pulleys G G, and trough M, arranged and operating substantially as described.

E. F. SHERMAN.
